UNITED STATES PATENT OFFICE

2,505,490

HIGH CHAIR TRAY

Bernard J. Greenbaum, Weston, Conn.

Application January 22, 1947, Serial No. 723,635

8 Claims. (Cl. 155—127)

1

This invention relates to high chairs and more particularly to high chair trays. An object of the invention is to provide a tray which will be secure and firm but which nevertheless may be easily detached with one hand so that the child may be guided or held with the other hand. A further object of the invention is to provide a tray which may be selectively lifted over the head of the child and allowed to rest against the back of the chair or withdrawn directly and removed. A still further object is to provide a tray with positive gripping means and so constructed that there is no possibility of the tray coming loose when a child's weight is pressed against it. A still further object of my invention is to provide a tray which is adjustable so that it may be brought closer or farther away from the back to accommodate itself to the size of the child. Other objects and advantages of my improved tray will be apparent from the accompanying drawings and description.

In the accompanying drawings:

Fig. 1 is an inverted view of my improved tray showing the operating mechanism in a closed position fastened to the chair.

Fig. 2 is a partial view similar to Fig. 1 but with gripping means open for removal of the tray from the chair.

Fig. 3 is a cross-sectional view taken on the line 3—3 of Fig. 1 with the chair shown in outline for clarity.

Fig. 4 is a detailed enlargement showing the operation of the clamping means.

Fig. 5 is a cross-sectional view taken on the line 5—5 of Fig. 4.

Fig. 6 is a view showing a combined tray holder and arrester which is adapted to be used as a guard and tray holder.

Referring more particularly to the drawings, while I have shown a chair 10 of a particular type, it will be understood that my tray may be applied to practically any type or configuration of chair. Similarly, while I have shown a tray 15 of a definite configuration and shape this is of secondary importance and a square tray or oblong tray could be used as well. Fastened to the tray 15 is a plate 16 which may be screwed by means of the screws 17 or otherwise fastened to the tray. The plate 16 has an upturned flange 18 which serves a dual purpose. Extending through an opening in the flange 18 is an arm 19 carrying the operating handle 20. Fastened to the arm 19 at 21 is a spring 22 having its other end 23 engaging the flange 18. The arm 19 is fastened at its inner end to a bar 25 which is pro-

vided at either end with studs 26 extending through slots 27 in the plate 16. The slots 27 are substantially parallel to each other and in the same general plane as the arm 19. The arm 19 is also provided with a stud 28 which rides in the slot 29 in the plate 16 and engages the bar 25 thus limiting the movement of the bar 25. Pivotally mounted on the plate 16 are arms 30 pivoted at 31. The arms 30 are provided with gripping members 32 of channel formation and also are provided with slots 33 through which the studs 26 extend. The slots 33 are at an angle extending inwardly with relation to the slots 27 so that when the operating handle 20 is pulled toward the front of the tray the studs 26 riding in the slots 27 and 33 will cause the arm 30 to pivot on the point 31 outwardly and away from the center line of the tray. The inner portions of the gripping members 32 are provided with teeth 35. The chair is provided with a pair of brackets 40 the outer surface of which are serrated to form a plurality of teeth 41 adapted to mesh with and engage the teeth 35 on the gripping members 32. In operation the tray is placed on the chair by the simple operation of pulling the operating handle 20 toward the front of the tray and sliding the gripping members 32 over the brackets 40 until the desired position is reached, at which time the handle is released. It will be noted that there are a number of teeth 41 to allow the tray to be positioned in a number of selective points. When it is desired to remove the tray it is only necessary to exert pressure on the operating handle and to pull the tray away from the chair. As shown in Fig. 6, I provide a combined tray holder and guard 45 which is pivoted at 46 to the back of the chair. This is provided with teeth 47 similar to the teeth 41 and with a bar 48 extending across the front of the chair. This can be used as shown in Fig. 6 simply as a guard to prevent the child from falling out of the chair and can be swung over the back of the chair when it is desired to fasten the tray rigidly to the brackets 40 or may be used as a tray holder with the gripping members 32 gripping the teeth 47. With this alternative the entire tray may be swung over the back of the chair and allowed to remain on the tray holder and guard 45. It will be appreciated that any modification of my invention can be made such as the use of a leaf spring positioned against the flange 18 and against the bar 25 without departing from the spirit and basic concept of my invention. It will also be appreciated that the plate 16 may be built into the tray in numerous

2

ways but that regardless of how it is positioned it provides a simple method of operation.

I claim:

1. The combination with a chair, of fixtures fastened to each side thereof, a tray, arms pivotally mounted on said tray, spring means for normally tensioning said arms towards each other thus engaging said fixtures, and a handle operatively connected to said arms to force them in the opposite direction.

2. The combination with a chair, of serrated fixtures fastened to each side thereof, a tray, serrated arms pivotally mounted on said tray, spring means for normally tensioning said arms towards each other thus engaging said fixtures, and a handle operatively connected to said arms to force them in the opposite direction.

3. The combination with a chair, of serrated fixtures fastened to each side thereof, a tray, arms pivotally mounted on said tray, each of said arms having a channel serrated on the inner surface thereof, spring means for normally tensioning said arms towards each other thus causing the engagement of the said serrated channel of each arm with the serrated portion of each fixture, and a handle operatively connected to said arms to force them in the opposite direction.

4. The combination with a chair, of a tray, fixtures fastened to said chair, means for detachably fastening said tray to said fixtures, including a plate having parallel slots at each end, an arm pivotally mounted on each end of said plate having slots therein extending at an angle to said plate slots, gripping means on the end portions of said arms, a bar with a stud on each end portion of said bar extending through the aforementioned plate slot and arm slot, and an operating handle engaging said bar to move it in relation to said plate causing said arms to pivot on said plate engaging and disengaging said fixtures.

5. In a chair tray, a pair of serrated arms, spring means tensioning said arms towards each other, a bar engaging said arms by pin-and-slot connections, and an operating handle attached to said bar the movement of which against the urging of said spring means causes said bar to move said arms away from each other.

6. The combination with a chair, of serrated fixtures mounted on said chair so as to pivot over the back thereof, a tray, serrated arms pivotally mounted on said tray, spring means for normally tensioning said arms towards each other thus engaging said fixtures, and a handle operatively connected to said arms to force them in the opposite direction.

7. The combination with a chair, of serrated fixtures secured to said chair, a tray, a plate, serrated arms pivotally mounted on said plate, a bar, studs on said bar, slots in said plate and said arms for slidably engaging the studs on said bar and guiding the movement thereof, a handle engaging said bar whereby the movement of the handle in one direction causes the movement of the bar and the studs thereon to cam against the arms causing said arms to move outwardly releasing them from the fixtures and thus freeing the tray from the chair, and releasing the handle causes a reverse action and the arms to move inwardly, the serrated portions thereof engaging the serrated portions of the fixtures thus securing the tray to the chair.

8. The combination with a chair, of serrated fixtures secured to said chair, a tray, a plate fastened to said tray, a bar positioned between said plate and said tray, slots parallel to each other in the end portions of the plate, arms pivotally mounted on said plate, each of said arms having a channel serrated on the inside thereof, inwardly angled slots in said arms, studs on said bar extending through the slots in the plate and the slots in the arms, a handle, a shaft as part of said handle, a stud on said shaft which engages said bar and passes through a slot in said plate and a spring connecting the shaft on the handle to the plate whereby when the handle is pulled forward the bar riding on the stud of the handle shaft is pulled forward imparting a forward motion to the studs on said bar riding along the parallel plate slots and the angled arm slots, camming said arms outwardly and disengaging the arms from the fixtures thus releasing the tray from the chair and when said arms are placed in juxtaposition to said fixtures and the handle released a reverse action takes place causing said arms to be drawn inwardly, the serrated channels thereof engaging the serrated portions of said fixtures thus securing the tray to the chair.
